ATTORNEY.

UNITED STATES PATENT OFFICE.

BEATRICE M. BENNETT, OF PHILADELPHIA, PENNSYLVANIA, ASSIGNOR TO INTERNATIONAL ART PUBLISHING COMPANY, OF PHILADELPHIA, PENNSYLVANIA, A CORPORATION OF PENNSYLVANIA.

PICTORIAL DEVICE.

1,379,739.

Specification of Letters Patent. Patented May 31, 1921.

Application filed May 3, 1920. Serial No. 378,492.

To all whom it may concern:

Be it known that I, BEATRICE M. BENNETT, a citizen of the United States, residing in the city and county of Philadelphia, State 5 of Pennsylvania, have invented certain new and useful Improvements in Pictorial Devices, of which the following is a specification.

My invention relates to improvements in 10 pictorial devices, and particularly to pictorial devices which are self-supporting.

My invention resides in a pictorial device comprising a display card and a collapsible supporting member, base or easel secured to 15 the display card, which in its open or supporting position forms a receptacle.

For an illustration of one of the forms my invention may take, reference is to be had to the accompanying drawing, in which:

20 Figure 1 is a perspective view of a display card and the supporting member or easel in open position.

Fig. 2 is a vertical section of the parts shown in Fig. 1 on a plane extending transversely of the display card and supporting member.

Fig. 3 is a plan view of a piece of material shaped and marked with dot and dash lines for folding to form the collapsible base 30 member and receptacle.

Fig. 4 is a view showing the display card with its supporting or base member folded for insertion into an envelop.

Referring to Figs. 1, 2 and 4, 1 is a display 35 card which may be of any desired size, shape or outline and may carry upon its face or faces any desired picture, legend or printed matter. The display card may be formed of any suitable material, such as paper, 40 paper board, paste board, bristol board, card board, sheet metal or wood. A feature of my invention resides in the fact that the display card does not or need not serve as a supporting element and its base need not 45 be square or straight, but may be curved or rounded as shown.

On one face of the display card, which I shall hereinafter refer to as the rear face, is secured the collapsible combined receptacle and supporting member 2. Member

50 2 is in the form of a rectangular receptacle of any suitable material, such as paper,

paper board, card board, paste board, bristol board, preferably resilient and stiff, whereby it may be bent and folded and form a 55 substantial support for the display card. It may be formed by folding, creasing and pasting a sheet of material, as is well understood in the art. In Fig. 3 I have shown the shape of a piece of material with the lines 60 on which the material is to be creased or folded indicated by dot and dash lines for forming the collapsible rectangular receptacle shown in Figs. 1, 2 and 4.

The supporting member 2 is secured to the 65 rear face of the display card in any suitable manner, for example, by means of an adhesive, with one of its flat sides, preferably the bottom adjacent the lower edge of the display card 1.

In Fig. 4 I have shown a display card with 70 its combined receptacle and supporting member in folded or collapsed position, in which condition the device is flat and may be inserted into a flat envelop 3.

My display device may be embodied in a calendar, picture or other pictorial or advertising device, or in a valentine, favor, postal card or the like. It may be folded to 75 form a flat body for packing and shipping 80 or mailing, and when in use the display card 1 is supported in upright position and serves its usual purpose, while the supporting member 2 serves as an easel and a receptacle for pins, matches, candy, etc. 85

What I claim is:

1. A display device comprising a display member and an easel therefor consisting of a receptacle open at its top and having up-standing sides and a horizontal bottom, said 90 sides and bottom being permanently secured to each other at their adjoining edges, one of said sides attached to said display member with its plane parallel to the plane of said display member, said sides except the 95 one attached to said display member, folding into parallelism with said one of said sides, and said bottom folding parallel with said display member, said receptacle both when folded and extended being disposed 100 entirely on one side only of said display member.

2. A display device comprising a display member and an easel therefor consisting of

a support-engaging bottom and a side up-
standing from an edge of said bottom at-
tached to said display member parallel
thereto, and creased sides forming with said
5 side and bottom a receptacle open at its top,
said last named sides and said bottom fold-
ing against said display member parallel

therewith, said receptacle both when folded
and extended being disposed entirely on one
side only of said display member.

In testimony whereof I have hereunto
affixed my signature this 30th day of April,
1920.

BEATRICE M. BENNETT.
